CHILD'S FLOAT OR SIMILAR ARTICLE

William Finley Moore, Lake City, Fla.

Application July 6, 1948, Serial No. 147,405

Term of patent 3½ years

(Cl. D34—15)

To all whom it may concern:

Be it known that I, William Finley Moore, a citizen of the United States of America, residing at Lake City, in the county of Columbia and State of Florida, have invented a new, original, and ornamental Design for Child's Float or Similar Article, of which the following is a specification, reference being had to the accompanying drawing, forming part thereof, wherein:

Fig. 1 is a sectional view taken on the line 1—1 in Fig. 2 of a child's float or similar article, showing my new design;

Fig. 2 is a top plan view thereof; and

Fig. 3 is a front elevational view thereof.

I claim:

The ornamental design for a child's float or similar article, as shown.

WILLIAM FINLEY MOORE.
